TOY FISH

Emmett White, Fayetteville, N.C., assignor to Christy Manufacturing Company, Inc., Fayetteville, N.C., a corporation of North Carolina

Filed Dec. 31, 1962, Ser. No. 73,023

Term of patent 3½ years

(Cl. D34—2)

FIG. 1

FIG. 2

I claim:

The ornamental design for a toy fish, substantially as shown.
